UNITED STATES PATENT OFFICE.

JOHN SEAZHOLTZ AND MICHEAL BILANCIA, OF NEWARK, NEW JERSEY.

FIREPROOF PROTECTIVE LEGGING.

Application filed December 6, 1923. Serial No. 678,972.

To all whom it may concern:

Be it known that we, JOHN SEAZHOLTZ and MICHEAL BILANCIA, both citizens of the United States, residing at Newark, in the 5 county of Essex and State of New Jersey, have invented certain new and useful Improvements in Fireproof Protective Legging; and we do hereby declare the following to be a full, clear, and exact description 10 of the invention, such as will enable others skilled in the art to which it appertains to make and use the same, reference being had to the accompanying drawings, and to characters of reference marked thereon, which 15 form a part of this specification.

This invention relates, generally, to improvements in a fire-proof protective legging for metal moulders and similar artisans; and the invention has for its principal 20 object to provide a novel construction of legging made of asbestos material, so shaped and constructed that the same may be easily and quickly put on over the ordinary clothes of the wearer, and which, when 25 so worn, serves to adequately protect the leg, thigh and hip of the workman against spillings and splashings of molten metal handled by the latter during casting or similar operations.

Another object of this invention is to provide a legging which by virtue of its novel shape and construction not only provides adequate protection but is of such character as not to interfere with or impede the 35 movements of the workman when carrying on his work.

The invention also has for its further objects to provide various detail improvements in the fastening and supporting means for 40 the novel legging, as well as in the general construction and make up of the same.

The invention is clearly illustrated in the accompanying drawings, in which:—

Figure 1 is a pictorial view of a workman 45 clothed in the novel construction of fire-proof protective legging made according to and embodying the principles of this invention; Figure 2 is an outer side elevation of the novel legging; Figure 3 is a front elevation of the same; Figure 4 is an inner side view of the legging opened up so that the same may be put on or taken off the leg of the workman; Figure 5 is an inner side view of the legging closed; Figure 6 is a fragmentary vertical section, on an enlarged scale, taken on line 6—6 in Figure 4; Figure 7 is a fragmentary transverse section, taken on line 7—7 in Figure 6; Figure 8 is a fragmentary transverse section drawn on an enlarged scale, taken on line 8—8 in Figure 60 4; Figure 9 is a fragmentary transverse section drawn on an enlarged scale, taken on line 9—9 in Figure 4; Figure 10 is a vertical cross section on an enlarged scale, taken through the bottom strap of the legging; Figure 11 is a perspective view of the metal protector plate which is attached to the underside of the bottom strap; and Figure 12 is a fragmentary vertical section on an enlarged scale, taken on line 12—12 in 70 Figure 1.

Similar characters of reference are employed in all of the hereinabove described views, to indicate corresponding parts.

Referring now to said drawings, the reference character 13 indicates the complete legging made according to and embodying the principles of this invention. The body of the legging is made of a suitable fire-proof or non-combustible material, such, for example, as asbestos cloth. The legging comprises an upper, permanently closed, cylindrical section 14 which is adapted, when worn, to encircle the thigh of the wearer from the knee upward. Suitably and permanently affixed to the lower end of section 14 is a lower section 15, the connection of said sections 14 and 15 being preferably effected by sewing the parts together and to end by the stitching 16. Said lower section 75 80 85 90 95 100 105 110 is discontinuous throughout its length on the inner side thereof, so that the same may be opened up to permit the passage of the foot of the wearer therethrough, and thus is provided on the inner side with over-lapping or meeting longitudinal free edge-portion 17 and 18. The edge portion 17 is the interior edge-portion and the edge portion 18 is the exterior edge portion. Said lower section 15 tapers toward its lower extremity to conform more or less to the diminishing contours of the lower leg of the wearer, and the lower extremity of said section 15 terminates, at its front side, in a forwardly extending flared portion forming a gaiter portion 19 to extend over and cover the instep and foot of the wearer. Suitably and permanently affixed to the upper end of the section 14 is an upward extension or flap to form a hip-protector portion 20. The connection of said section 14 and said hip-protector portion 20 is preferably effected by

sewing the parts together end to end by the stitching 21.

The main body portion of the legging, constructed and assembled as above described, is reinforced and strengthened at the front and back, by stitching to the inner side thereof longitudinal reenforcing strips 22 and 23, preferably made of textile material, such as canvas or the like, or of leather or any other strong flexible material.

The lower leg portion of section 15 is further reenforced and strengthened, and secured against sagging or undue wrinkling, by means of a light flat steel strip 24, which is placed so as to extend longitudinally from the lower end at one side of said section 15 upward to the knee. Said steel strip 24 is secured in place by cover strip 25 of textile or other suitable material, which is fastened to the section 15 by lines of stitching extending parallel to and along each side of the steel strip 24. The said steel strip 24 is held against longitudinal displacement by pocket members 26 which are respectively stitched to the body of the section 15, so as to receive and enclose respectively the upper and lower ends of said steel strip. In like manner, said section 15 is additionally reinforced and secured against sagging or undue wrinkling, by means of a second flat steel strip 27 disposed to extend along the inner side of the exterior free longitudinal edge portion 18, the same being secured in place by a cover strip 28 of textile or other suitable material.

Suitable fastening devices 29, having their cooperative parts suitably secured to the respective free longitudinal edge portions 17 and 18 of the section 15, are provided in order to hold the said section 15 of the legging closed about the lower leg and foot of the wearer, when said legging is worn.

In order to hold the legging down around the leg, and to guard against the lower end of the same working up and thus uncovering the foot of the wearer, a bottom strap 30 is provided, which is attached to one side of the bottom marginal portions of the legging so as to cross under bottom of the instep of the foot of the wearer, the free end of the strap 30 being adapted to be operatively held by a buckle device 31 which is secured to the opposite bottom marginal portion of the legging. In order to prevent charring and consequent weakening of the strap 30 by reason of contact thereof with particles of hot metal upon which the wearer may step, the outer or under side of the strap is covered by a protector strip or shoe 32 preferably made of sheet metal, and fastened to the strap by rivets 33, or any other suitable fastening means.

The means for supporting the legging upon the person of the wearer comprises a

suspension strap 34 which is secured to the upper free end of said hip-protector portion 20 so as to extend longitudinally upward therefrom. The reference character 35 indicates a hook member, to the base of which 70 is connected a buckle 36 with which the free end of the suspension strap 34 may be adjustably fastened to couple the hook member 35 thereto. When the legging is placed upon the leg of the wearer, the hook member 75 35 is engaged over the belt supporting the ordinary trousers of the workmen, or, if no belt is worn, over the waist-band of the trousers, thus suspending the legging and holding the same up in operative position 80 to properly enclose the leg and cover the hip of the wearer. The legging thus supported allows for perfect freedom of leg movement by the wearer, and yet is comfortable while being securely held in operative relation to the wearer's leg. The suspension strap 34 being adjustable, through the buckle connection 36, relative to the hook member 35, the support of the legging may be easily regulated or adjusted according to the height of the wearer or the length 85 of the wearer's leg, and so as not to cause undue pulling strains upon the belt or trouser waist-band.

The novel construction of the legging above described is particularly effective for moulders' use when carrying on casting operations. It is well understood that in such work it is required to handle and carry about ladles filled with molten metal, and that frequently the metal slops over from the ladle, and also splashes and spatters about when poured. Under such circumstances, burning particles of metal fly out against the leg of the workman nearest the 105 ladle, with the result that not only are the clothes scorched and burned, but frequently the workman's leg is painfully and severely burned. Furthermore, the molten metal is often accidentally spilled against the leg or 110 foot of the workman, thereby causing painful and disabling injuries. The present invention provides a fire-proof protective legging which not only covers the lower leg, but the thigh and hip as well, on the side 115 of the workman adjacent to which the ladle is carried, thus adequately protecting both the clothes and person of the wearer. The novel legging is so designed that the provision of the upper closed section and the 120 lower openable section, renders the same very easy of manipulation in putting the same on and off the leg, and, the novel means of supporting the legging is not only very simple and easy of attachment, but serves to 125 hold the legging supported in such manner as not to interfere with either the comfort or the free movement of the wearer.

We are aware that some changes may be made in the various arrangements and com- 130

binations of the several devices and parts making up the novel legging, as well as in the details of the construction of the same, without departing from the scope of this invention as set forth in the foregoing specification, and as defined in the appended claims. Hence, we do not limit our invention to the exact arrangements and combinations of the several devices and parts as described in said specification, nor do we confine ourselves to the exact details of the construction of said parts as illustrated in the accompanying drawings.

We claim:—

1. A fire-proof protective legging, comprising a tubular upper section, a lower section adjoining said upper section which is discontinuous on its inner side to provide longitudinal meeting edges, mutually cooperative fastening devices at said meeting edges to hold the same closed together, a hip-protector flap adjoining the upper end of said upper section, and a suspension means attached to the free upper end of said hip-protector flap.

2. A fire-proof protective legging, comprising a tubular upper section, a lower section adjoining said upper section which is discontinuous on its inner side to provide longitudinal meeting edges, mutually cooperative fastening devices at said meeting edges to hold the same closed together, a gaiter portion at the lower extremity of said lower section to cover the foot of the wearer, a transverse keeper-strap connected with said gaiter portion to extend under the foot of the wearer, a hip-protector flap adjoining the upper end of said upper section, and a suspension means attached to the free upper end of said hip-protector.

3. A fire-proof protective legging, comprising a tubular upper section, a lower section adjoining said upper section which is discontinuous on its inner side to provide longitudinal meeting edges, mutually cooperative fastening devices at said meeting edges to hold the same closed together, a gaiter portion at the lower extremity of said lower section to cover the foot of the wearer, a transverse keeper-strap connected with said gaiter portion to extend under the foot of the wearer, a hip-protector flap adjoining the upper end of said upper section, and a suspension means attached to the free upper end of said hip-protector, comprising a supporting strap, a hook-element, and a buckle attached to said hook element with which the free end of said supporting-strap may be adjustably connected.

4. A fire-proof protective legging, comprising a tubular upper section, a lower section adjoining said upper section which is discontinuous on its inner side to provide longitudinal meeting edges, mutually cooperative fastening devices at said meeting edges

to hold the same closed together, a hip-protector flap adjoining the upper end of said upper section, and a suspension means attached to the free upper end of said hip-protector flap, comprising a supporting strap, a hook-element, and a buckle attached to said hook-element with which the free end of said supporting-strap may be adjustably connected.

5. A fire-proof protective legging, comprising a tubular body tapering toward its lower end, the lower extremity of said body being flared at its forward side to cover the foot of the wearer, the lower portion of said body being split longitudinally to provide longitudinal meeting edges, mutually cooperative fastening devices at said meeting edges to hold the same normally closed together, and a hip-protector flap connected with and extending upwardly from the upper end of said body.

6. A fire-proof protective legging, comprising a tubular body tapering toward its lower end, the lower extremity of said body being flared at its forward side to cover the foot of the wearer, the lower portion of said body being split longitudinally to provide longitudinal meeting edges, mutually cooperative fastening devices at said meeting edges to hold the same normally closed together, a hip-protector flap connected with and extending upwardly from the upper end of said body, a suspension means comprising a supporting strap, and a hook-element with which the free end of said strap is adjustably connected.

7. A fire-proof protective legging, comprising a tubular body tapering toward its lower end, the lower extremity of said body being flared at its forward side to cover the foot of the wearer, the lower portion of said body being split longitudinally to provide longitudinal meeting edges, mutually cooperative fastening devices at said meeting edges to hold the same normally closed together, longitudinal reinforcing steels arranged at each side of the lower portion of said body at the inside surface thereof, means for retaining said steels in position, and a hip-protector flap connected with and extending upwardly from the upper end of said body.

8. A fire-proof protective legging, comprising a tubular body tapering toward its lower end, the lower extremity of said body being flared at its forward side to cover the foot of the wearer, the lower portion of said body being split longitudinally to provide longitudinal meeting edges, mutually cooperative fastening devices at said meeting edges to hold the same normally closed together, longitudinal reinforcing steels arranged at each side of the lower portion of said body at the inside surface thereof, means for retaining said steels in position,

and a hip-protector flap connected with and extending upwardly from the upper end of said body, a suspension means comprising a supporting strap, and a hook-element with 5 which the free end of said strap is adjustably connected.

9. A fire-proof protective legging, comprising a tubular body tapering toward its lower end, the lower extremity of said body 10 being flared at its forward side to cover the foot of the wearer, the lower portion of said body being split longitudinally to provide longitudinal meeting edges, mutually cooperative fastening devices at said meeting edges to hold the same normally closed together, longitudinal reenforcing steels arranged at each side of the lower portion of said body at the inside surface thereof, means for retaining said steels in position, a 15 hip-protector flap connected with and extending upwardly from the upper end of said body, a suspension means comprising a supporting strap, and a hook-element with 20 which the free end of said strap is adjustably connected, and a transverse keeper strap connected with the bottom extremity of said lower portion of said body.
- 25 10. A fire-proof protective legging, comprising a tubular body tapering toward its lower end, the lower extremity of said body

being flared at its forward side to cover the foot of the wearer, the lower portion of said body being split longitudinally to provide 30 longitudinal meeting edges, mutually cooperative fastening devices at said meeting edges to hold the same normally closed together, longitudinal reenforcing steels arranged at each side of the lower portion of said body at the inside surface thereof, means for retaining said steels in position, a 35 hip-protector flap connected with and extending upwardly from the upper end of said body, a suspension means comprising a 40 supporting strap, and a hook-element with which the free end of said strap is adjustably connected, and a transverse keeper strap connected with the bottom extremity 45 of said lower portion of said body.

In testimony, that we claim the invention set forth above we have hereunto set our hands this 3rd day of December, 1923.

JOHN SEAZHOLTZ.
MICHEAL BILANCIA.
